Assistant Examiner—Susan Bennett Hattan

(74) Attorney, Agent, or Firm—Daniel M. Cislo, Esq.; Cislo & Thomas, LLP

(57) **CLAIM**

The ornamental design for a shroud, as shown and described.

DESCRIPTION

FIG. 1 is a right side view of a shroud, the left side view being a mirror image thereof;

FIG. 2. Is a top view thereof;

FIG. 3. Is a bottom view thereof;

FIG. 4. Is a rear view thereof; and,

FIG. 5. Is a front view thereof.

The broken line portions of the disclosure are for illustrative purposes only and form no part of the claimed design.
